UNITED STATES PATENT OFFICE.

ROBERT H. WHITE, OF EVERETT, WASHINGTON.

AERIAL LOGGING SYSTEM.

1,411,144.

Specification of Letters Patent. Patented Mar. 28, 1922.

Application filed January 27, 1921. Serial No. 440,439.

To all whom it may concern:

Be it known that I, ROBERT H. WHITE, a citizen of the United States, residing at Everett, in the county of Snohomish and State of Washington, have invented certain new and useful Improvements in Aerial Logging Systems; and I do declare the following to be a full, clear, and exact description of the invention, such as will enable others skilled in the art to which it appertains to make and use the same.

This invention relates to an improved aerial logging system or railway and one object of the invention is to provide a railway of the character described in which the fall block may be drawn downwardly from the carriage and to one side of the carriage and trolley cable upon which the carriage moves, the carriage swinging transversely upon the trolley cable when the fall block is drawn to one side.

Another object of the invention is to so construct the carriage that the hoisting line upon which the fall block is mounted may extend through the carriage in a straight line when the fall block is drawn upwardly thus permitting the weight of the load to be evenly distributed upon the trolley cable and hoisting cable.

Another object of the invention is to so construct the carriage that the trolley cable and hoisting cable may extend through the carriage between side plates thereof and between upper and lower rollers positioned between the side plates, the hoisting cable when drawn tight serving not only as a second trolley cable but further serving as means engaged by the lower rollers to prevent the carriage from moving upwardly.

Another object of the invention is to so construct this carriage that the fall block when drawn upwardly will be out of engagement with the lower and upper rollers engaged by the trolley cable and hoisting cable.

Another object of the invention is to so construct this railway that the carriage may be readily moved longitudinally thereof and stopped at any desired point upon the trolley cable and the fall block permitted to move downwardly with the carriage at any desired point upon the trolley cable.

Another object of the invention is to so construct this railway that the haul back line for the fall block may be selectively

extended to draw the fall block to either side of the trolley cable.

Another object of the invention is to so construct this railway that no brakes are necessary for the carriage and no positive connection is necessary between the fall block and carriage.

Another object of the invention is to so construct this railway that the hoisting cable, haul back line or cable, and lines connected with opposite end portions of the carriage may be wound upon separate drums of an engine thus permitting each line to be provided with separate winding means for drawing upon the line or releasing the line when desired.

Another object of the invention is to provide a railway which will be comparatively simple in construction and in which the carriage will be of a simple construction and very strong and durable and not liable to jam upon the trolley cable or hoisting cable.

This invention is illustrated in the accompanying drawings, wherein:

Figure 1 is a perspective view showing the logging system or railway in operation.

Figure 2 is an enlarged fragmentary view showing the carriage and fall block in elevation, a portion of one of the side plates of the carriage being broken away.

Figure 3 is a longitudinal sectional view through the carriage taken along the line 3-3 of Fig. 2.

This improved logging system or railway is intended to be used for moving logs from the point at which they will rest when the trees are cut and divided into logs to a point where the logs are to be piled ready for loading upon a railway logging train. This aerial railway is provided with standards or posts 1 and 2 which may if so desired, be formed by placing posts similar to telegraph posts into the ground but which will preferably be formed by selecting trees at a suitable distance apart and cutting the limbs and upper portion of the trunk away thus leaving the balance standing to form the post or standard. Pulleys 3, 4, 5, 6 and 7 are connected with the upper portion of the post or standard 1 and pulleys 8 and 9 are connected with the upper portion of the post or standard 2.

At suitable points, trees will be cut thus leaving stumps 10, 11, 12, 13, 14 and 15 and pulleys 16 will be connected with the stumps 11, 12 and 13 and similar 110

pulleys 17 will be connected with the stumps 14 and 15. The pulleys 17 will be so connected with the stumps 14 and 15 that they can be easily disconnected and moved over 5 and connected with similar stumps 14' and 15' upon the opposite sides of the posts 1 and 2. It will thus be seen that the haul back line or cable 18 which is wound upon the drum 19 of the stationary engine 20 and 10 passed through the pulleys 6 and 17, may be caused to extend upon either side of the posts or standards 1 and 2 desired.

The carriage 21 is mounted upon a trolley cable 22 which extends through the pulleys 15 3 and 8 and has one end portion connected with the stump 13 and the second end portion connected with the stump 10. This trolley cable will be stretched tight so that the carriage can move easily along the same 20 from one post or standard to the second. This carriage is constructed as shown in Figs. 2 and 3 and from an inspection of these figures, it will be seen that the carriage is provided with side plates 23 which 25 are connected by rivets 24 upon which are placed spacing sleeves 25 engaging the inner faces of the side plates and thus holding the side plates in spaced relation. Upper rollers or rods 26 are mounted between the 30 side plates and these upper rollers rest upon the trolley cable 22. Lower rollers 27 are rotatably mounted between the side plates and beneath the rollers 26 and engage the hoisting cable 28 which extends through the 35 carriage between the side walls and beneath the trolley cable 22. It will thus be seen that both of these cables extend between the side plates and between the upper and lower rollers, the upper cable 22 engaging the 40 rollers 26 and the lower cable 28 engaging the rollers 27. This hoisting cable 28 is connected with the post or standard 2 and after passing through the carriage 21 is engaged with the pulley 4 carried by the post 45 or standard 1 and wound upon the drum 29 of the hoisting engine. The fall block 30 is mounted upon the hoisting line 28 between the rollers 27 and from an inspection of Figs. 1 and 2, it will be seen that the side 50 plates are cut out between the rollers 27 thus providing a pocket 31 to receive the fall block when the hoisting cable is drawn tight. When this hoisting cable is drawn tight, the fall block and the portion of the cable between the rollers 27 will assume the position 55 indicated by dotted lines. It will thus be seen that this hoisting cable will extend through the carriage in a straight line so that a great deal of the weight of the logs 60 connected with the haul block will be taken by the hoisting line. The fall block will be prevented from coming into engagement with the rollers 26 or 27 and also kept from coming into engagement with the 65 trolley cable 22 by the side plates and fric-

tion will thus be prevented and also danger of jamming prevented. When the hoisting cable or line is drawn tight, the carriage will be prevented from moving upwardly and therefore the rollers 26 cannot 70 jump off of the trolley cable 22.

In order to impart movement to the carriage, there has been provided a main pull line 32 which is wound upon the drum 33 of the engine 20 and after being passed through the pulley 5 is connected with one end of the carriage by means of the shackle 34. A second pull line 35 which may be termed a snubbing line is wound upon the drum 36 of the hoisting engine and after 75 being passed through the pulleys 7, 16 and 9, will be connected with the second end portion of the carriage by means of the shackle 37. By proper operation of the hoisting engine mechanism which is well known, one of the pull lines may be released and the second drawn upon thus permitting the carriage to be moved along the trolley cable towards the pole or standard 1 or 80 towards the pole or standard 2. When the carriage has reached the desired point, rotation of these drums may be stopped and the carriage will be held in a set position. If it is then desired to draw the fall block 85 downwardly, the drum 19 will be rotated and the haul back line or cable 18 which is connected with the fall block as shown in Fig. 1 will be drawn upon to draw the fall block downwardly towards the ground. By 90 having the pulley 17 connected with the proper stump, the fall block will be drawn towards one side so that the hooks of the fall block may be connected with the log or logs to be lifted. Of course, when the fall block is being drawn downwardly, the drum 95 of the hoisting line will be permitted to rotate freely. After the hook of the fall block has been connected with the log or logs, the haul back line will be permitted to 100 unwind from its drum and the hoisting line will be wound upon its drum to draw the fall block upwardly to the dotted line position. During this lifting movement, the carriage will have turned transversely upon the trolley cable and will thus be positioned 105 at the proper angle for the most effective lifting of the load. As soon as the hoisting line has been drawn tight, rotation of its winding drum will be stopped and the drum 36 will be released and the drum 33 rotated 110 to wind the main pull line 32 upon its drum. This will cause the carriage to move along the trolley line or cable towards the standard 1 and the fall block will of course be pushed along the hoisting line with the carriage. 115 During the lifting process, the weight will be carried almost entirely by the trolley cable but after the hoisting line has been drawn tight, the fall block will rest upon the tightly drawn cable which will now con- 120 125 130

stitute the trolley cable and this cable 28 together with the cable 22 will support the load. After the carriage has been moved to the desired point, the drums of the cables 5 32 and 35 will be held against rotation by suitable brake means and the hoisting cable released and permitted to unwind from its drum. The fall block will be carried downwardly by the weight of the load carried. 10 It will thus be seen that during the lifting process, the carriage may be held stationary upon the trolley cable and prevented from having a tendency to move along the same during the lifting process. It will be further noted that the carriage may swing transversely upon the trolley cable during the lifting process thus permitting the carriage to assume the proper angle for the effective raising of the load and drawing 15 of the logs along the ground before the actual lifting is commenced. It will be further noted that the carriage may be easily moved longitudinally of the trolley cable with the hoisting cable assisting in carrying 20 the load and further that when the carriage has been returned to the desired position for a second load, the fall block may be effectively drawn downwardly towards the ground and to one side.

25 30 I claim:

1. A logging system comprising a trolley cable, a carriage slideable upon said trolley cable, a fall block separate from said carriage, a hoisting cable passing through said carriage and fall block and extending in a straight line when drawn tight with the fall block drawn up its full extent, and means for moving the carriage along the trolley cable with the fall block resting upon and 35 moving along the tightened hoisting cable.

2. A logging railway comprising a trolley cable, a hoisting cable beneath said trolley cable, a carriage having upper runners resting upon said trolley cable and lower runners positioned beneath said hoisting cable, and a fall block mounted upon said hoisting cable between the lower runners and movable upwards to a point permitting said hoisting cable to extend in a straight line 40 through said carriage.

3. The structure of claim 2 having the carriage provided with spaced side plates having the upper and lower runners between the same and the cables extending between 45 the side plates and between the upper and lower runners, the intermediate portions of the side plates being cut to provide a pocket receiving the fall block when the hoisting cable is drawn tight.

4. A logging railway comprising a trolley 60 cable, a carriage slideable thereon, a hoisting cable extending through said carriage, a fall block mounted upon said hoisting cable intermediate the length of said carriage, the carriage being permitted of side swing when 65 said hoisting cable is slack, lines connected with said carriage for moving the carriage along said trolley cable, a line connected with said fall block for drawing the fall block down with the hoisting cable released, 70 and means for drawing upon and releasing said cables.

5. A logging system comprising an aerial support, a carriage slidably mounted thereon, a hoisting cable passing through the carriage, a fall block mounted upon the hoisting cable intermediate the length of said carriage, means for moving the carriage longitudinally upon the aerial support, and means for drawing the fall block downwardly and to one side, the carriage turning to one side upon the aerial support when the fall block is drawn downwardly and to one side.

6. A logging system comprising an aerial 85 railway including a trolley cable, a carriage slideable upon the trolley cable, a fall block, a hoisting cable passing through the carriage and engaging the fall block, the hoisting cable when drawn upon to raise the fall 90 block being drawn tight and constituting an auxiliary trolley cable having the fall block slidably mounted thereon, and means for moving the carriage longitudinally upon the trolley cable.

7. An aerial logging system comprising an aerial railway having a trolley cable, a carriage slideable upon the trolley cable, a load carrier, and means for drawing the load carrier up into close proximity to said carriage constituting a trolley cable having the load carrier slideable thereon when said means is drawn tight.

8. A logging system comprising an aerial railway, a carriage slideable longitudinally 105 of the aerial railway, a load carrier, means for drawing the load carrier upwardly into close proximity to said carriage constituting a track member for the load carrier when the load carrier is in a raised position, and 110 means for imparting movement to said carriage along said railway, the carriage when moving along the aerial railway engaging the load carrier and moving the load carrier along its track member.

115 In testimony whereof I have hereunto set my hand.

ROBERT H. WHITE.
